UNITED STATES PATENT OFFICE.

NORMAN C. DAVIS, OF PERTH AMBOY, NEW JERSEY, ASSIGNOR TO STANDARD UNDER-GROUND CABLE COMPANY, OF PITTSBURGH, PENNSYLVANIA, A CORPORATION OF PENNSYLVANIA.

TAPING MACHINE.

Application filed May 21, 1924. Serial No. 714,836.

To all whom it may concern:

Be it known that I, NORMAN C. DAVIS, residing at Perth Amboy, in the county of Middlesex and State of New Jersey, a citizen of the United States, have invented or discovered certain new and useful Improvements in Taping Machines, of which improvements the following is a specification.

My invention relates to machinery for feeding a strip of paper or other insulating material of similar form to the surface of a conductor; this feeding of a strip is part of the operation of building up, upon the surface of the conductor, of an envelope of insulation, of greater or less depth. That is to say, it concerns primarily machinery for building electrical cables; but, as will be manifest after reading the ensuing specification, the invention is applicable whenever such an operation is to be performed, whatever be the specific materials, and whatever be the character of and the utility of the finished article.

This application is filed in substitution for, and is a continuation in part of, an application filed by me July 7th, 1922, Serial No. 573,424.

In the accompanying drawings, Fig. I is a view in side elevation of a cable-taping machine, in which my invention is embodied; Fig. II is a view to larger scale and in transverse vertical section of the same machine, on the plane indicated at II-II, Fig. I. Fig. II is in some respects diagrammatic, for the reel is shown without the tension device. Figs. III, IV, and V are views drawn to still larger scale and showing the reel in vertical and medial section, in side elevation, and in end elevation, respectively. From Fig. III, as from Fig. II, the tension device has for clearness of illustration been omitted. Fig. VI is a fragmentary view to still larger scale, showing in elevation the anchorage for the band of the tension device. Figs. VII and VIII are views corresponding to Fig. I, although drawn to larger scale, and fragmentary in character, illustrating permissible variations in detail. Fig. IX is a fragmentary view, corresponding to Fig. I, drawn to larger scale, and illustrating a supplementary adaptation. Fig. X is a plan view from above, showing, on larger scale than

Fig. I, a portion of the apparatus which in Fig. I is shown in side elevation. Figs. XI and XII are views in side elevation of alternately applicable sets of gears. Their place in the structure appears in Fig. X, and the two figures, XI and XII, taken in connection with Fig. X, will sufficiently illustrate an adaptation to be described in the ensuing specification.

I here show my tension device applied to and made part of a cable taping machine, in which the conductor under treatment advances along a straight-away course, adjacent to which course a tape reel is arranged, and relative movement is imparted to conductor and tape reel, such as to effect a drawing of the tape from the reel and a wrapping of the tape upon the conductor. In Letters Patent No. 1,450,584, granted April 3, 1923, to Standard Underground Cable Company, assignee of the applicants, of whom I was one, the support for the reel is stationary and the conductor rotates as it advances; in the machine illustrated here, the conductor has no motion of rotation, but the reel describes a planetary orbit around the line of conductor advance as a center. The effects in the two cases are, for present purposes, the same, and the applicability of the invention to either of the alternative arrangements indicated will be manifest, without further elaboration. It will be understood that the tension device of this application is applicable, wherever a strip is drawn from a reel and laid down upon the surface of a longitudinally advancing body. Indeed, in broadest aspect the invention so far as concerns reel structure alone is applicable, even to situations where there are no associated parts. With these prefatory remarks, I shall describe the invention in particular application to and as constituting part of the cable-taping machine of Figs. I and II.

In these drawings a drum 1 is shown trunnioned in a suitable frame, and this is the receiving drum for the taped conductor. The drum 1 is turned through suitable mechanical connections from a shaft 7, which in turn is driven from a suitable source of power. As drum 1 turns, in clockwise direction as shown in Fig. I, a conductor C supplied in continuous length advances

along a straight-away course until it is received by and wound upon the drum. As it advances along such straight-away course the conductor is enveloped in the 5 wrapped-on tape.

A cage surrounds conductor C advancing on the straight-away course mentioned. The drawings show two cages.

Giving attention to the individual cage, 10 it will be seen to consist of heads or spiders 3, connected peripherally by rods 4. The spiders are trunnioned by hollow trunnions in suitable standards 5, and are so placed with respect to the other parts of the machine that the conductor advancing on its 15 straight-away course to drum 1 passes freely through the hollow trunnions. That is to say, the cage surrounds the advancing conductor and is rotatable on the line of conductor advance as an axis. Means are 20 provided for rotating the cage, and such means may conveniently take the form of a sprocket drive 6 from shaft 7. Thus cable advance and cage rotation may be inter- 25 related and rendered synchronous. A clutch operating device is indicated at 8, and in it are found means for starting and stopping the machine at will. Such means of driving the cable and the tape reel in 30 synchronism admit of the use of removable and interchangeable driving members of different size to achieve different speed relationships, for ends presently to be defined. This is illustrated in Figs. X—XII. 35 The drum 1 is driven from shaft 7 through the set of gears 33, 34. The gears are borne on parallel shafts. It is a well known detail of engineering to provide in such case alternate sets of gears, such as 33—34 and 35—36, each set having the same center-to- 40 center distance, and so interchangeable upon the shafts, but the component pinions being of different relative size, and accordingly adapted to impart to the drum 1 different 45 speeds with respect to the rate of rotation of shaft 7. It will be perceived that by interchange of such sets of gears different speed relationships may be established between reel revolution and conductor ad- 50 vance.

Upon a rod 4 of the cage is mounted a tape reel 9. A suitable manner of mounting is sufficiently indicated in Fig. II; and it will be remarked of this manner of 55 mounting that it admits of adjustment of the reel 9 in its particular position longitudinally of rod 4, and that a set-screw 10 affords means for securing the reel in the position to which it may be brought. Fig. 60 II shows further the particular position of the reel in these respects, that the reel is remote from the conductor an appreciable distance, that the tape as delivered by the reel extends in a position transverse 65 to the length of the cable, that, more spe-

cifically, the axis of the roll of tape coiled upon the reel lies in a plane perpendicular to the axis of frame turning (that is, to the line of conductor travel), and that the tape advancing from the reel makes a turn, 70 specifically a quarter turn, in reaching its place on the surface of the conductor. On this latter point see the larger scale showing of Figs. III and IV. This transverse delivery has advantage, as presently will 75 appear; and the particular position of the reel makes possible further, either a right-hand or a left-hand wrapping of the tape upon the conductor, and wrapping upon conductors of varying size (within reasonable limits), without readjustments in position. The angle formed by the line of strip advance and the radial plane alluded to (cf. Fig. III) takes care of itself automatically, and increases as the depth of 80 the wrapping increases.

The primary advantage, due to this transverse delivery of the strip from the reel, and the consequent turning of the plane of the strip in its advance from reel to conductor, is this: If the delivery be (as hitherto has been sought) in a position parallel to the axis of the conductor, then, when the "lay" is to be changed—that is to say, the angle at which the helical twist is laid,—the position of the reel must be adjusted. And this adjustment is troublesome, difficult; it must be done by the "cut-and-try" method, and consumes a great deal of time. I find that by giving up the idea that the strip as delivered from the reel should extend in a plane parallel with the axis of the conductor, and by so placing it that the delivery is actually transverse, I may disregard the particular position of the reel when a change is to be made in the lay. As I have said, the position of the reel which I preferably adopt is that shown in the drawings, where the strip as delivered extends perpendicularly to the axis of the conductor. I find with this arrangement that change of lay may be effected by change in the relative speeds of conductor advance and of orbital reel revolution, and that as such change is made the feeding of the strip from reel to conductor adjusts itself automatically to the changed conditions.

It will be understood without elaboration that a plurality of reels may be so mounted upon the rods of the frame, and that adjustment of the reels one to another along the rods will determine the interval at which the tapes are successively applied to the conductor. And of course successive frames may carry successive reels or groups of reels. When more than one frame is used, one frame may be rotated in one direction and another in opposite direction, to effect opposite wrapping. Referring particularly to 120 125 130

Fig. IX, instead of the sprocket drive 6 of Fig. I, a bevel-gear drive, the well known alternate for a sprocket drive, is shown, and this bevel-gear drive includes a reversing

5 clutch 32 of familiar form. As this clutch is shifted to complete driving connection through one or the other of its pinion members, the frame is rotated in one direction or the other. And where there is a plurality 10 of frames, as shown in Fig. I, the provision of such a drive as Fig. IX illustrates makes possible any desired combination in the matter of direction of rotation and in consequent direction of lay.

15 29 is a guide for the conductor C, and its purpose is to hold the conductor against distortion under the strain of wrapping. This is a feature dwelt upon in the companion patent to which allusion has already been 20 made.

By such means the conductor as it advances may be enveloped in layers of wrapped on tapes, in such number and to such depth, and with such reversals of 25 direction of wrapping as may be required.

I have just explained, with the arrangement shown in Fig. I particularly in mind, that as reel 9 is shifted longitudinally upon rod 4 of the cage, the point may be adjusted, 30 where the particular strip is laid down upon the growing cable. In Figs. VII and VIII I show reels 9 which are not themselves adjustable. In one case the reel is carried by the head 3 of the cage, in the other by 35 the rod 4, but in the latter case it may be immovable longitudinally upon the rod. But in each case a guide 31 is provided, over which the strip passes, on its way from the reel to the growing cable, and this guide is 40 adjustable longitudinally of the cage, upon rod 4, to accomplish the same end which in the structure of Fig. I, is by adjustability of the reel longitudinally of the cage, accomplished.

45 In Fig. VII also indication is afforded, how from a plurality of non-adjustable reels a plurality of strips may be taken and laid down at successive and adjustably fixed points.

50 My further description will have to do with features shown more particularly in Figs. III-VI.

A pan conveniently formed of metal and consisting of a circular plate 11 with a marginal flange 12, and provided with a central hub 13 is suitably mounted on a transversely extending axis adjacent the path of advance of conductor C. Fig. II, as has been remarked, shows a suitable mode of mounting on one of the rods 4 of the frame already described. This pan and its hub have no motion of rotation. A roll of tape when applied is rotatable on hub 13, as presently will be more fully explained. The outer face 65 of marginal flange 12 is truly cylindrical

and smooth. The flange is cut away throughout a part (ordinarily a relatively small part) of its extent. This cutting-away is indicated at a, Fig. IV. A cover plate 14 is removably mounted on hub 13 70 and it is adjustable in its mounting and when brought to position is secured by wing nut 15. Both pan and cover are provided with openings, conveniently opposite in their locations, through which the extent to which 75 a roll of tape has been used, may be perceived. Fig. IV shows such an opening b in pan 11.

A flexible band 16, ordinarily of metal, smooth-faced on its under side, overlies flange 12, and means are provided for holding the band under tension, constricted upon flange 12. The band in its placement and in its holding means leaves uncovered and free of access the opening already indicated, at a, but it advantageously extends, as best shown in Fig. IV, throughout the greater portion of the extent of flange 12, and, in the manner presently to be described, frictionally engages the advancing tape over approximately 180° of the circumferential extent of flange 12. At one end the band 16 may be anchored by a stud 17 to a bracket 18 carried by plate 11 (cf. Figs. IV and VI); at its opposite end band 16 is 95 secured to a slide 19.

Upon two brackets 20 and 21, also carried by plate 11, are borne aligned guides, 22, 23, and in these guides a rod 24 is mounted to slide. A spring-backed latch 25 with a 100 press button 28 for release, holds rod 24 in the position shown in Figs. IV and V. The rod 24, it will be remarked, extends in the mid-plane of flange 12 and, but for a narrow space, is tangent to the circle of flange 12, and extends in such position circumferentially, that the slide 19 in which band 16 terminates, is a slide upon rod 24. 105

Rod 24 is screw threaded toward its upper end and carries upon its screw-threaded portion an adjustable nut 30. A spring 27 engaging nut 30 and slide 19, tends to shift slide 19 downwardly on rod 24; a spring 26 engaging guide 23 and slide 19 tends to shift slide 19 upwardly against spring 27. 110 Normally, latch 25 being in engagement with a notch formed in rod 24, the rod is secured against upward movement in its slideway, and both springs are held under compression. 115

Band 16 normally encircles flange 12, as indicated in Figs. IV and V. The strength of spring 27 so far exceeds that of spring 26, that, when the parts are assembled as shown, band 16 is held to flange 12, or to a tape overlying flange 12, under a yielding pressure, whose value is the excess of the power of spring 27 over spring 26. That excess is adjustable, by the turning of nut 30. When the latch is opened, by pressure 120 125 130

upon button 28, both springs expand, rod 24 is shifted upwardly, slide 19 also is shifted upwardly, and the constriction of band 16 is relieved.

- 5 When the machine is to be made ready for use, cover 14 is removed, and a roll of tape T, which ordinarily will be carried on a spool B, is slipped upon hub 13, in such position that in unwinding the rotation is 10 in clockwise direction (Fig. IV), and the end of the roll is carried out through the opening α in flange 12. Cover 14 is replaced, moved inward until the spool is carried home, and then slightly withdrawn, 15 before wing nut 30 is turned and the cover secured. The free end S of the coil of tape is then (band 16 being in inactive and slack position) carried over the outer face of flange 12 and between flange 12 and band 20 16 and beyond the end of band 16 tangentially to conductor C, and it is secured to the surface of conductor C in usual manner. The rod 24 is then depressed (it is for that purpose provided with terminal knobs), 25 until the latch 25 engages its notch. The band 16 is thus constricted upon the strip of tape facing flange 12. The degree of constrictive stress—the strength of the tension upon the tape—is, by the turning of 30 nut 30, adjustable.

- With attention upon Fig. IV, the direction of right-line travel of conductor C will be noted; it is, as here shown, from right to left, in the direction indicated by arrow τ . 35 As the conductor advances the reel moves bodily in planetary orbit around the cable as a center. This planetary movement of the reel causes the tape to be drawn from the reel and wrapped upon the conductor, 40 in the manner diagrammatically shown.

The tension is such as to blanket and render of no practical effect minor irregularities in resistance to unwinding, but the feed of the tape is smooth and regular, and 45 the tape is laid down upon the conductor without wrinkle, firmly, and securely. The tension is constant, whether the spool of paper be full or nearly run out, and there is no tearing of the tape through irregularities in tension.

The degree of tension may, as has been said, be varied, as conditions may require or suggest.

When the end of a spool of tape is approaching, the fact may be noted, the machine may at the proper moment be stopped, and a full spool may be substituted for the empty one. The machine may then be started again. There is a minimum loss of waste 60 ends of tape.

This removal of an empty spool and replacement of it by a full one is a very simple matter; the machine is stopped, latch 25 released, cover 14 removed, the empty spool 65 taken out, a new one put in, the new end led

out through the opening in the flange, cover 14 replaced, the new tape slipped between flange and band 16 and secured, perhaps to the cable, perhaps to the end of the previously applied tape. Rod 24 is then slid 70 downward until latch 25 again secures it, and the reel is ready for renewed operation.

When in the continued operation of the machine a change in lay is desired, no other adjustment is required than such interchange 75 of driving parts as shall cause conductor advance and reel revolution to assume a new speed relationship. The feed of the strip will as has been explained accommodate itself automatically to the change. It is requisite in such a machine, in order to produce a uniform article,—and practically perfect uniformity is required,—that the tape shall be laid down substantially free of distortion strain, and that the point where the tape 80 meets the cable body shall, other things being equal, be invariable longitudinally along the path of advance of the cable body, regardless of whether the coil or tape within the tape-reel be a new coil or a coil nearly 85 exhausted. Or, in common parlance, there shall be no creep of the tape at the point where it meets the cable body.

These ends are gained, first of all, by eliminating as a significant factor in the operation of the machine, the frictional resistance of the coil of tape to unwinding. I provide a tension device which engages the paper after it has been uncoiled; I so mount the coil of tape within the reel that its resistance to unwinding is insignificant, and within my tension device I so powerfully engage the tape that the constant pull upon the tape necessary to draw it through the tension device 90 is incomparably greater than the variable 95 pull necessary to unwind the dwindling coil.

With attention centered on Fig. III it will be remarked that the line of pull exerted to draw the strip S from the reel and wrap it upon the cable body C is not exactly in the center plane of the coil T but is slightly angular thereto, and it will be perceived that as the cable body varies in size the line of pull will vary in this angularity. Now, by mounting the spool B which carries the coil 100 T so that it can turn with the utmost freedom upon the hub 13, and by applying the wrapping-resisting tension to the tape as it advances over flange 12, not only is that tension rendered constant, but certain other 105 good results follow, which are essential to successful machine operation and the production of a uniform product. One of these good results has already been mentioned; it is that the diminution in the size of the coil 110 T as the strip unwinds and is used up, has no effect to disturb the wrapping operation.

There is on that account no irregularity in wrapping. Second, the tape leaves the coil 115 T with the utmost freedom. The angling of 120 the strip as it passes over flange 12, and the resulting variation in the angle of the tape 125 as it is wound upon the conductor C, is entirely removed. The result is a uniform article, 130

the tape on its path to the conductor, a feature just mentioned, does not bring a focus of strain at the point where the tape leaves the coil, where there would be danger of 5 tearing. Instead, the tension is exerted upon the tape after it has advanced from the coil and lies upon flange 12 and beneath band 16. A third good result is this,—I have spoken of the angularity of the strain of wrapping 10 with relation to the center plane of the coil, and have remarked that that angularity is one which is variable, even though minutely. Now the tape encircling flange 12 and overlain by band 16 adjusts itself in position. 15 The path of the tape does not change abruptly at the point where the tape passes from beneath band 16, but the tape assumes an angular path over the whole extent of flange 12; it lies in helical course upon flange 20 12. And because of the relatively great extent of flange 12, the angle of the line of wrapping strain to the mid-plane of the coil, instead of being wide, as would be the case were the strip taken directly from the coil, 25 is reduced to insignificant dimension. Furthermore, the minute variations due to variations in the diameter of the cable body are reduced practically to the vanishing point. Incidentally, I call attention to the 30 fact, as shown in Fig. III, that the face of flange 12 is wider than the tape. Thus provision is made for that automatically assumed helical position of the tape upon the flange which I have just indicated. These 35 minute matters become matters of first importance in the building of a cable, where the utmost precision to achieve substantially undeviating uniformity in product, is requisite. 40 Certain variations in structure illustrated in Fig. VII become noteworthy here. It will be remarked that the tape leaving the reel 9, before it reaches the guide 31 passes over a drum 37. It will be remarked further that the reel 9 is turned, so that its 45 mid-plane is transverse to the cable axis, while the axis of drum 37 extends in a plane perpendicular to the cable axis, and the surface of drum 37 is tangent to the 50 mid-plane of reel 9. In Fig. VII the tension band is for the sake of simplicity of showing omitted from the reel. It will be understood that in this case there will be no helical displacement of the strip as it 55 advances over the outer surface of the reel, but that the helical displacement will automatically occur upon the surface of drum 37, precisely as in the form shown in Fig. III it occurs upon the surface of flange 12. 60 And by enlarging the surface over which that helical displacement occurs, its effect as a disturbing factor in manufacture is reduced to the vanishing point, and is in the structure shown actually eliminated. 65 It may further be remarked of the struc-

ture of Fig. VII, and the same is true of Fig. VIII, that the position of the bolt of paper 9 may be varied. The bolt may be placed in such position as will be most economical from the point of view of machine designing and yet the abutment 31 being present, operation in the manner and to the ends described will not be disturbed. 70

I have used the word "conductor" throughout this specification as a general 75 term, inclusive of a bare wire, and of a partially completed cable as well.

I claim as my invention:

1. A tape reel including a cylindrical case adapted to contain a roll of tape, the 80 side wall of such cylindrical case being ori-ficed for the passage through of the strip of tape advancing from the roll within, and a friction band carried by the case and adapted to bear yieldingly and with con-85 strictive force upon a web of tape advanc-ing through the orifice in the side wall of the casing and overlying the side wall exteriorly.

2. A tape reel including a cylindrical 90 case adapted to contain a roll of tape, the side wall of such cylindrical case being ori-ficed for the passage through of the strip of tape advancing from the roll within, a 95 friction band anchored at one end to said case and adapted to overlie externally the cylindrical wall of the case, a slideway borne by said case, and yielding means re-sisted by constriction of said band exterior-100 ly upon said case for advancing the other- 100 wise free end of said band along said slide-way.

3. In a cable-taping machine, means for causing a cable body to advance on a straight-away course, a cage surrounding 105 such course and rotatable on the mid-line of such course as an axis, a tape-reel borne by said cage, a positioning abutment ar-ranged intermediate tape-reel and cable-110 body course and adjustable longitudinally along the course of the cable body.

4. A tape-reel including a cylindrical case, means for sustaining a coil of paper freely 115 rotatable within the case, the case itself being ported in its cylindrical wall, and means 120 cooperating externally with the cylindrical wall of the case for exerting tension upon a length of paper advancing from the coil within, through the port, and over the case wall exteriorly.

5. In cable-making apparatus means for 125 sustaining a length of unfinished cable in straight-away course, means for sustaining a coil of tape adjacent to such course, means for imparting to cable and to tape-coil rela-tive motions of longitudinal advance and of planetary revolution, an abutment with cylindrical surface arranged adjacent to and extending transversely to the length of cable over which abutment the tape may 130

advance from the coil to its place upon the cable, the said means leaving the tape free of lateral restraint as it advances to the said cylindrical abutment.

- 5 6. In cable-making apparatus means for sustaining a length of unfinished cable in straight-away course, means for sustaining a coil of tape adjacent to such course, means for imparting to cable and to tape-coil relative motions of longitudinal advance and of planetary revolution, two cylindrical surfaces arranged on axes transverse to the cable course over which the tape is caused to advance on its way from coil to cable
- 10 body.
- 15 7. In the wrapping of tape upon a cable-body the method herein described which consists in leading the tape from an un-
- 20 coiling bolt in helical course over a cylindrical surface concentric with the bolt

and retarding the progress of the tape along such helical course.

8. In the wrapping of tape upon a cable-body the method herein described which consists in leading the tape from an un- 25 coiling bolt in helical course over a cylindrical surface concentric with the bolt and retarding the progress of the tape along such helical course, and wrapping the tape upon a surface extending transversely 30 to the axis of the body to be taped in its further progress from the cylindrical surface to the surface of the article to be taped.

In testimony whereof I have hereunto set 35 my hand.

NORMAN C. DAVIS.
